(57) **CLAIM**

We claim the ornamental design for a display screen with graphical user interface for a video pagination indicator, as shown and described.

DESCRIPTION

FIG. 1 is a view of a first image in the sequence of a first embodiment for a display screen with graphical user interface for a video pagination indicator.

FIG. 2 is a view of a second image thereof.

FIG. 3 is a view of a third image thereof.

FIG. 4 is a view of a fourth image thereof.

FIG. 5 is a view of a fifth image thereof.

FIG. 6 is a view of a sixth image thereof.

FIG. 7 is a view of a seventh image thereof.

FIG. 8 is a view of an eighth image thereof.

FIG. 9 is a view of a ninth image thereof.

FIG. 10 is a view of a tenth image thereof.

FIG. 11 is a view of an eleventh image thereof.

FIG. 12 is a view of a twelfth image thereof.

FIG. 13 is a view of a thirteenth image thereof.

FIG. 14 is a view of a fourteenth image thereof.

FIG. 15 is a view of a fifteenth image thereof.

FIG. 16 is a view of a sixteenth image thereof.

FIG. 17 is a view of a seventeenth image thereof.

FIG. 18 is a view of an eighteenth image thereof.

FIG. 19 is a view of a nineteenth image thereof.

FIG. 20 is a view of a twentieth image thereof.

FIG. 21 is a view of a twenty first image thereof.

FIG. 22 is a view of a twenty second image thereof.

FIG. 23 is a view of a twenty third image thereof.

FIG. 24 is a view of a twenty fourth image thereof.

FIG. 25 is a view of a twenty fifth image thereof.

FIG. 26 is a view of a twenty sixth image thereof.

FIG. 27 is a view of a twenty seventh image thereof.

FIG. 28 is a view of a twenty eighth image thereof; and,

FIG. 29 is a view of a twenty ninth image thereof.

The appearance of the image transitions sequentially between the images shown in FIGS. 1-29. The process or period in which one image transitions to another forms no part of the claimed design.
